UNITED STATES PATENT OFFICE.

ARCHIBALD McGUGAN AND HENRY SPRAGG, OF HAMILTON, ONTARIO, CANADA.

CLOCK.

1,039,165.

Specification of Letters Patent. Patented Sept. 24, 1912.

Application filed November 18, 1911. Serial No. 660,962.

To all whom it may concern:

Be it known that we, ARCHIBALD McGUGAN and HENRY SPRAGG, both subjects of the King of Great Britain, and residing at

5 Hamilton, in the county of Wentworth and Province of Ontario, Canada, have jointly invented new and useful Improvements in Clocks, of which the following is a specification.

10 Our invention relates to improvements in clocks, and consists of visible means connected therewith, to indicate the time for winding the clock and for winding the alarm of the clock.

15 The objects of our invention are first to provide means for visibly indicating when the clock should be wound, and should not be wound; second, to provide means for visibly indicating when the alarm mechanism of 20 the clock, should be wound, and should not be wound, thereby avoiding any inadvertent mistake, or confusion.

We attain these objects by the mechanism illustrated in the accompanying drawing, in 25 which:—

Figure 1 is a sectional elevation of a circular casing of a clock, the stationary framework in the clock, together with the main shaft and its spring, and the alarm shaft 30 with its spring, these several parts are not new. Fig. 2 is a side elevation of a detached indicator shaft with an adjustable indicating disk thereon, and a worm wheel on the lower end thereof geared into a worm 35 wheel on the rotary alarm shaft of the clock, one end of said shaft being broken away.

Similar characters of reference refer to similar parts throughout the several views.

In the drawing 1, is the circular casing 40 of a clock, 2, is stationary framework in said casing, and rigid therewith, 3, is the main shaft provided with a main coil spring 4, and 5 is the alarm shaft provided with a coil spring 6. The several parts thus far indicated and referred to by numerals, are not 45 new, and are common in clocks of various constructions, and which we do not desire to claim.

Various kinds of mechanism including 50 gear wheels and springs of various kinds for rotating the common shafts 3 and 5, referred to, are used in clocks, and are well known, these we prefer not to show, mention, nor to claim, in order that our invention may be set forth in its simplicity, therefore devoid of complicated combinations of

old systems of wheels and intermediate wheels geared one into the other, and almost numberless, and other well known mechanical elements.

60 Our invention consists of a suitable bearing or support 8, rigidly secured to the common frame 2 of the clock and at a suitable angle thereto by means of screws 9. 10, is an indicating shaft, adapted to rotate in 65 said bearing, one-half revolution in a period of time, and is provided with a collar 12, to rest on the upper end part of the bearing as a guiding and retaining means for the shaft. The lower end of the shaft 10, is provided 70 with a worm wheel 13, secured thereon, and which gears into the worm wheel 14, which is secured on the common main shaft 3, which rotates the shaft 10, by means of said worm wheels.

75 15, is a disk provided with a suitable lower socket 16, adapted to receive the upper end part of the shaft 10 which extends beyond the casing 1, and said disk is adjustably secured to the shaft by means of a suitable 80 screw 17, on the rear side thereof, a similar screw 28 being shown in Fig. 2, of the drawing.

Fig. 2 of the drawing serves to illustrate 85 the indicating shaft 10, together with its indicating disk 15, and its other parts connected therewith; also the indicating shaft 20, together with its indicating disk 25, and its other similar parts connected therewith.

18, is a bearing, or support, rigidly secured 90 to the common frame 2, of the clock, and at a suitable angle thereto, by means of screws 19.

20, is an indicating shaft at an angle to the clock, adapted to rotate in said bearing, 95 and adapted to make one-half revolution in a period of time, and is provided with a collar 21, to rest on the upper end part of the bearing, as a guiding and retaining means for the shaft. The lower end of the shaft 100 is provided with a worm wheel 22, secured thereon, and which gears into a worm wheel 23, which is secured on the common alarm shaft 5, which rotates the shaft 20, by means of said worm wheels.

105 25, is a disk provided with a suitable lower socket 26, adapted to receive the upper end part of the shaft 20, which extends beyond the casing 1, and said disk is adjustably secured to the shaft by means of a suitable 110 screw 28, on the rear side thereof and shown in Fig. 2, of the drawing.

It is our intention to have the words "Wind clock" or the word "Clock" on the face of the disk 15, and the face of the disk 25, to bear the words "Wind alarm" or the word "Alarm."

The disks 15, and 25, each make one-half revolution in a period of time, and the adjustable mechanism of the disks is, to allow the disks to be adjusted that the faces thereof 10 shall be parallel with the face of the clock, or with the clock, as shown in Fig. 1, when said disks require to be set, this setting of the disks would be necessary upon the introduction of our invention in a clock.

15 When the ordinary mechanism of an alarm clock is run down, and therefore ready to be wound, the mechanism comprising our invention is in position, as shown, the disks being parallel one with the other, 20 and with the clock, and readable as shown.

Our invention is adapted for connection with clocks of various makes, and constructions, and which now exist, or to clocks in course of construction, and new clocks, especially to that class of clocks known as 25 alarm clocks.

To place our invention in clocks already made, all that is necessary is to secure the worm wheel 14, on the main shaft 3, or the 30 worm wheel 23, on the alarm shaft 5, the other mechanism connected therewith, as shown and described, may then be easily placed in position.

The main spring shaft 3, and the alarm 35 shaft 5, each make about eight revolutions in twenty four hours, and the worms connected therewith are proportioned in order that the indicating shafts 10 and 20 shall each make one-half revolution in a predetermined period of time.

What we claim as our invention and desire to secure by Letters Patent, is:—

1. In a clock, a rigid frame, a bearing

rigidly secured thereto, an indicating shaft adapted to rotate in the bearing and one 45 end of said shaft extending beyond the common casing of the clock, an adjustable indicating disk secured to the extended end of the shaft, a worm wheel secured on the opposite end of the indicating shaft, a worm 50 wheel secured on a common rotating shaft of the clock adapted to gear into the worm wheel on said indicating shaft to rotate the indicating shaft one-half revolution in a period of time. 55

2. In a clock, a rigid frame, a bearing rigidly secured thereto, an indicating shaft adapted to rotate in said bearing, and one end of the shaft extending beyond the common casing of the clock, an adjustable indicating disk on the extended end of the shaft, a worm wheel secured on a common rotary 60 shaft of the clock adapted to engage with a worm wheel on the opposite end of the indicating shaft, adapted to rotate said indicating shaft one-half revolution in a period of time. 65

3. In a clock, a rigid frame, a bearing secured thereto, an indicating shaft adapted to rotate in said bearing, means on the 70 shaft to retain the same in operative and rotary position, one end portion of the shaft extending beyond the casing of the clock, an adjustable indicating disk secured to the extending end of the shaft, a rotary 75 shaft of the clock, a worm wheel on said shaft and a worm wheel on the opposite end of the indicating shaft adapted to engage one with the other, whereby the indicating shaft together with the disk may revolve so one-half revolution in a period of time. 80

ARCHIBALD McGUGAN.
HENRY SPRAGG.
